UNITED STATES PATENT OFFICE.

OSCAR A. STINSON, OF DENVER, COLORADO.

NEWSPAPER-FILE.

1,177,550.

Specification of Letters Patent. Patented Mar. 28, 1916.

Application filed June 12, 1915. Serial No. 33,840.

To all whom it may concern:

Be it known that I, OSCAR A. STINSON, a citizen of the United States, residing at Denver, in the county of Denver and State 5 of Colorado, have invented new and useful Improvements in Newspaper-Files, of which the following is a specification.

This invention relates to paper files or 10 holders and more particularly to newspaper files.

One of the principal objects of the invention is to provide a device of this character which will securely hold a single paper or 15 a plurality of papers with equal firmness.

Further objects of the invention will appear as the following specific description is 20 read in connection with the accompanying drawings which form a part of this application and in which:—

Figure 1 is a plan view with the parts 25 broken away, Fig. 2 is a an edge view, Fig. 3 is a transverse sectional view on the line 3—3 of Fig. 1, Fig. 4 is a side elevation of a key used in connection with the lever included in the locking mechanism.

Referring more particularly to the drawings 30 1 and 2 represent the clamping members, the former of which is provided with fastening devices such as wood screws 3 for attaching the same to a table or other similar support, while the latter is provided with short screws 4 to give the device a uniform appearance. The members are held against longitudinal displacement by the

guiding pins 5 seated in sockets 6 in the member 1 and arranged to extend in sockets 35 7 in the member 2. Surrounding these guide pins and arranged in the sockets 6 and 7 are spiral springs 8 normally tending 40 to press the clamping members apart as will be readily understood. The clamping member 2 is provided with a plurality of penetrating prongs 9 adapted to enter recesses and pockets 10 provided therefor in the 45 member 1.

Secured to the edge of the member 1 is a face plate 11 which carries bearing arms 12 extending into the mortise 13 made to accommodate the same. At the outer end of 50 each arm 12 there is secured a pivot pin 14 upon which is pivoted the forked end 14'

of a lever 15 extending through a slot in the face plate as shown. Pivoted between the ends of the forked portion 14' of the lever 15 is an angular link 16 which connects with the spring hanger 17 by means of a hook 18. The spring hanger is firmly embedded or secured within the member 2 at its free end and projecting into a recess or mortise arranged to accommodate the link and hook 60 18. When the lever is drawn into the position shown in dotted lines in Fig. 1 the springs 8 will force the clamping members apart equally at both ends so as to facilitate the insertion of a paper. After the paper 65 has been inserted the lever is drawn into the position shown in full lines which brings the pivotal point of the links 16 with the lever 15 beyond the center so as to automatically lock the lever in operated position. 70 The lever preferably is provided with a key-hole in its outer end for the insertion of any suitable type of key which is used to throw the lever to the position shown in dotted lines. 75

What is claimed is:—

1. In a newspaper file comprising a pair of clamping members, means normally acting to hold the members in separated position, guiding means, a lever pivoted to one 80 of the members, means connecting the lever and the other member which when the lever is operated causes the members to be drawn together, said means including a resilient part. 85

2. A newspaper file comprising a pair of parallel clamping members, springs normally acting to hold the clamping members in separated position, guiding means for said members, a lever having a forked end 90 pivoted to one of the members, a link pivoted to the forked end of the lever intermediate its ends, a spring hanger connected to the other member, and a hook between the spring hanger and the link, said lever 95 arranged to draw the members together.

3. A newspaper file comprising a pair of parallel clamping members, springs normally acting to hold the clamping members in separated position, guiding means for 100 said members, a lever having a forked end pivoted to one of the members, a link piv-

oted to the forked end of the lever intermediate its ends, a spring hanger connected to the other member, a hook between the spring hanger and the link, said lever arranged to draw the members together and penetrating prongs carried by one of the members.

In testimony whereof I affix my signature in presence of two witnesses.

OSCAR A. STINSON.
